UNITED STATES PATENT OFFICE.

JOHN M. HOPWOOD, OF DORMONT, AND THOMAS A. PEEBLES, OF PITTSBURGH, PENNSYLVANIA, ASSIGNORS TO THE HAGAN CORPORATION, OF PITTSBURGH, PENNSYLVANIA, A CORPORATION OF PENNSYLVANIA.

BLAST-NOZZLE.

1,381,306.

Specification of Letters Patent. Patented June 14, 1921.

Application filed April 21, 1919. Serial No. 291,478.

To all whom it may concern:

Be it known that we, JOHN M. HOPWOOD and THOMAS A. PEEBLES, residing at Dormont and Pittsburgh, respectively, in the county of Allegheny and State of Pennsylvania, citizens of the United States, have invented or discovered certain new and useful Improvements in Blast-Nozzles, of which improvements the following is specification.

10 In order to maintain a maximum efficiency in conveying systems where the material is moved by currents produced by jets of steam or air, it is necessary that the nozzles should have certain predetermined dimensions, 15 shape and contour. By means of the location of these nozzles, it is usually difficult to make accurate measurements to ascertain when, by reason of the cutting action of the fluid passing through the nozzle, the shape, 20 dimensions, etc., of the nozzle have been so changed as to materially reduce the efficiency of the nozzles.

The invention described herein has for its object the provision of means whereby 25 audible or visible indications may be given in case of a change in dimensions or shape which would tend to reduce the efficiency of the nozzle. The invention is hereinafter more fully described and claimed.

30 In the accompanying drawings forming a part of this specification, Figure 1 is a sectional view of the improved nozzle and Fig. 2 is a similar view illustrating a modification of the construction shown in Fig. 1, and 35 Fig. 3 illustrates a further modification of the improvement.

In the practice of the invention the nozzle consists of inner and outer shells 1 and 2, the shell 1 being constructed internally with the 40 usual or any suitable dimensions. The external shell is made with substantially uniform internal dimensions for the reception of the inner shell which has its rear portion formed so as to fit slidably within the outer shell. The forward portion of the inner shell is made smaller than the internal diameter of the shell 2 and such reduced portion is adapted to slide through a collar 4 preferably formed independent of the outer 45 sleeve and screwing thereinto. The inner shell is held from rear movement by a ring 5 which will also prevent a leakage of steam in between the inner and outer shells. In order to prevent movement of the inner shell

due to pressure of fluid against its rear end 55 a suitable lock is provided. This lock should be of such a character that in case the inner shell is cut through by the fluid jet at any point adjacent to its discharge end, the lock will be broken thereby permitting of the 60 inner shell being forced forward sufficiently far to uncover the port 6, permitting the fluid under pressure to flow through the passage 7 and operate a signal such for example as the whistle 8. A convenient lock consists 65 of a piece of wire, preferably spring wire, 9, drawn into a groove 10 in the reduced portion of the inner shell and so located that the wire ring will bear against the collar. The wire ring is held in place in the groove 70 and against the collar in any suitable manner as for example by twisting together the ends as shown. The ring 9 being formed of spring wire will, as shown, when it is cut by the action of the fluid, spring out of the 75 groove and permit the inner sleeve to be forced forward uncovering the port 6. In order to insure the removal of the ring from the groove when cut, the rear wall of the groove is inclined so as to push the broken 80 ring outwardly.

In case cutting action should occur in the throat, a series of holes 10 are bored radially from the exterior of the inner shell into proximity to the inner surface of the shell. 85 These holes have their outer ends connected to the passage 7 so that fluid escaping through such holes will operate the signal.

As the operation of the nozzle is not usually desired after such cutting action as 90 will cause the operation of the signal, provision is made for operating a valve to prevent the further flow of steam through the nozzle. In the construction shown, a valve 11 is so connected by rods 12 to the inner shell that when the shell is forced forward 95 the valve will be drawn against a seat 13 at the entrance end of the nozzle as shown in Fig. 2.

As shown in Fig. 3 an electrically operated signal may be employed. In such case the ends of a circuit including a bell 13, and battery 14 are connected to contacts 15 arranged in the path of movement of the inner shell so that the circuit will be closed when 105 the shell is released.

We claim herein as our invention:

1. A fluid nozzle provided with a port

- for the escape of fluid from the nozzle in combination with a signal connected to said port, a movable member normally closing said port and adapted to be shifted to open said port by the fluid passing through the nozzle, and means for holding the member in normal position and adapted to be rendered ineffective by the cutting action of the fluid flowing through the nozzle.
- 10 2. A nozzle for fluids having in combination an outer shell, an inner shell adapted to be shifted by pressure of fluid flowing through the shell, a port in the outer shell adapted to be closed by the inner shell when 15 in normal position, means destructible by the cutting action of the fluid for holding the inner shell in normal position and indicating means operative by fluid escaping through the port.
- 20 3. A nozzle for fluids having in combination an outer shell and an inner shell movable in the outer shell by the pressure of fluid flowing through the inner shell, a lock for holding the inner shell in normal 25 position and adapted to be destroyed by the action of fluid flowing through the inner shell, and indicating means operative on the movement of the inner shell from normal position.
- 30 4. A nozzle for steam or air blasts having

in combination therewith an indicating means, a movable member controlling the operation of the indicating means and movable by the pressure of the fluid flowing through the nozzle, and a lock for holding the movable member stationary and adapted to be broken by the action of the fluid flowing through the nozzle. 35

5. A nozzle for steam or air blasts having in combination a movable member adapted to be shifted by the fluid flowing through the nozzle, and indicating means, a valve for checking the flow of the fluid through the nozzle, said indicating means and valve being operative on the movement of the 40 movable member from normal position, and a frangible lock for holding the movable member in normal position.

6. A nozzle having in combination therewith an indicating means, a movable member controlling the operation of the indicating means, and means for holding the movable member in normal position and adapted to be cut away by the action of the fluid to release the movable member. 45 50 55

In testimony whereof we have hereunto set our hands.

JOHN M. HOPWOOD.
THOMAS A. PEEBLES.
